BOILER

Wilbur H. Armacost, New York, N. Y., assignor to
The Superheater Company, New York, N. Y.

Application January 18, 1935, Serial No. 2,337

11 Claims. (Cl. 122—303)

This invention relates to baffles for boilers of the straight tube type having the generating tubes thereof arranged in vertically spaced banks.

In a common type of boiler there are inclined generating tubes arranged in upper and lower banks which are spaced vertically and provide a so-called "interdeck space" in which a superheater may be located. In many such installations a baffle is run along the upper surface of the lower bank of tubes for a portion of their length and thence upwardly across the interdeck space and through the tubes of the upper bank. It is, of course, necessary to support this baffle and it is also desirable to cool it. One arrangement which has heretofore been proposed for this purpose is to provide a special row of tubes connected, for example, between the feed headers of the lower bank and the riser headers of the upper bank with these tubes bent in Z form so that they extend across the interdeck space and their end portions extend partially along each bank of tubes in parallelism with the latter adjacent the headers. Such an arrangement is shown in Patent No. 1,896,241, issued to J. F. Kavanagh and dated February 7, 1933.

However, the use of such Z-tubes to support the baffle ordinarily requires the use of special headers at the lower end of the lower bank and at the upper end of the upper bank since it is necessary to provide one more horizontal row of openings for connecting these tubes into these downcomer and riser headers. Alternatively, the use of similar headers at opposite ends of each bank requires plugging up a horizontal row of tube openings in one header of each bank.

One feature of the present invention is that it overcomes the above mentioned disadvantages by utilizing corresponding horizontal rows of tube openings in the headers of one of the banks for connecting the ends of generating tubes that provide a water cooled support for the baffle.

Another feature resides in simplifying the boiler construction.

Other features and advantages of the invention will become apparent upon consideration of the following detailed description of illustrative embodiments of the invention and the appended claims when read in conjunction with the accompanying drawing in which:

Fig. 1 is a side elevation in diagrammatic outline of a boiler embodying the invention;

Figs. 2, 3, 4, and 5 are similar views illustrating modified forms of the invention;

Fig. 6 is a view on the line 6—6 of Fig. 1 and illustrates one manner of connecting contiguous

sections of the baffle supporting tubes where such tubes are interrupted between the ends thereof that are connected to the headers; and

Fig. 6A is a view similar to Fig. 6 but shows a modified form of connection for contiguous sections of the baffle supporting tubes.

Referring to the drawing, the numeral 10 designates a boiler of well known type having an upper inclined bank of straight generating tubes 12 and a lower bank of similar tubes some of 10 which appear at 14. The banks comprising tubes 12, 14 are vertically spaced to provide an interdeck space 16 in which a superheater unit 18 is located at one side of a baffle 20. The baffle 20 extends vertically downward between the tubes 12 near their centre points, across the interdeck space 16 and thence laterally and downwardly parallel to the uppermost row of tubes 14 to the lower end of the bank of which tubes 14 are a part so as to form one side of the first gas 20 pass through the boiler.

In order to protect the baffle 20 in the part below tubes 12 I provide a water cooled support for it including a row of tubes 22 connected to the downcomer and riser headers 24 and 26, respectively, of the upper bank and comprising all or some of the lowermost row of tubes of this bank. The tubes 22 are bent between their ends, in roughly U-shape, so that intermediate portions of the tubes are deflected away from the other rows of tubes of the upper bank into the interdeck space 16. End parts of the intermediate or U-portions of these tubes extend across the interdeck space 16 to adjacent the lower bank and intervening parts extend in spaced relation to the tubes 12 of the upper bank and along part of the top of the lower bank closely adjacent thereto. To be more specific, in each of the various arrangements shown the tubes 22 extend from riser headers 26 parallelly along tubes 12 to near baffle 20 and thence downward across the interdeck space 16 along the vertical portion of baffle 20 to adjacent the tubes 14.

In Fig. 1 the tubes 22 are then bent to extend parallel to the tubes 14, continuing beneath the vertical part 20a of baffle 20 and along a portion of the upper side of the inclined part 20b of the baffle and then upward to the downcomer headers 24 of the upper bank. The arrangement of Fig. 4 is generally similar to that of Fig. 1 except that tubes 22 include reverse bends 28 and bowed portions 30 connected to the downcomer headers 24 of the upper bank. By providing the bowed portions 30 in the tubes 22 the interdeck space between the parts 20a, 20b of the baffle is utilized.

so that longer tubes 22 may be employed with resulting increase in the absorbing surfaces of these tubes. In Fig. 2 the part 20a of the baffle is continued along the upper side of the inclined parts of tubes 22 paralleling the tubes 14 of the lower bank, so that portions of the baffle extend partially above and partially below these parts of the tubes 22. In the arrangement shown in Fig. 3, the tubes 22 extend from headers 24, 26 10 paralleling tubes 12 to adjacent the part 20a of baffle and thence downward across the interdeck space at opposite sides of the part 20a of the baffle.

In Figure 5, the tubes 22 are shown connected 15 to the headers 39, 40 for the lower bank of tubes 14 rather than those of the upper bank. However, this arrangement is deemed less advantageous than those illustrated in Figures 1 to 4 because 20 the fact that the temperature of steam and water in the downwardly extending portions 42 of the tubes would be higher than in upwardly extending portions 44.

It should be understood that in each of the 25 various arrangements described above the tubes 22 may be continuous as shown in Figs. 2 and 4 or may comprise two sections 22a and 22b, as in Figs. 1 and 3, connected at their inner ends to 30 horizontally disposed header boxes 34. All of the tubes 22a, 22b may be connected into a single header box 34 or the tubes may be divided into groups with the tubes of each group connected into a header box common thereto. Alternatively, 35 individual header boxes may be provided for the sections 22a, 22b of each tube 22, as shown in Fig. 6A.

Packing 36 is preferably provided at the junction of the parts 20a, 20b of the baffle to prevent 40 leakage of flue gases from the first pass. It should be noted that in Fig. 3 the header box or boxes 34 are located between parts 20a, 20b of the baffle and form a part thereof.

It may be seen that the utilization of the lowermost horizontal row of tube openings in each 45 header of the upper bank for the tubes supporting the baffle in accordance with the invention obviates the necessity of employing special headers at one end of each bank of tubes, as is ordinarily the case where Z-tubes provided for supporting 50 the baffle are connected between the uppermost row of tube connections in the feed headers of the upper bank and the lowermost row of connections in the riser headers for the upper bank. That is to say, the invention dispenses with the 55 use of special headers at one end of both banks, which have one more horizontal row of tube openings than in the headers at the opposite end of the respective banks. Nor is it necessary to plug 60 horizontal rows of tube connections or openings in the feed headers for the lower bank and in the riser headers for the upper bank, as when using similar conventional headers at opposite ends of each bank in order to avoid the use of such special headers for connecting the tubes supporting 65 the baffle. In short by deflecting intermediate portions of a row of generating tubes, connected into the lowermost horizontal rows of tube openings in the upper bank headers, from parallelism with the other rows of tubes of the bank, in accordance with the invention, the boiler construction 70 is simplified. This is because the baffle is efficiently cooled and supported while at the same time it is not necessary to provide a special header or an extra row of tubes for supporting the baffle 75 in addition to those ordinarily present in the banks

nor is it necessary to provide any other type of special support for the baffle.

What I claim is:

1. In a boiler having a pair of vertically spaced banks of generating tubes, downcomer and riser headers for said banks, and a baffle structure extending through said upper bank, substantially vertically across the space between said banks and along part of the upper row of tubes in the lower bank to separate the first gas pass from the second; a row of tubes connected at opposite ends to the headers of one of said banks and each having an intermediate portion thereof deflected away from said one bank and extending along said vertically extending, interdeck portion of said 15 baffle structure for supporting the latter.

2. In a boiler having a pair of vertically spaced banks of inclined generating tubes, downcomer and riser headers for said banks, and a baffle structure extending through said upper bank, 20 across the space between said banks and along part of the upper row of tubes in the lower bank to separate the first gas pass from the second; a row of generating tubes having end portions connected to the lower parts of the headers of said upper bank and extending therefrom parallel to the tubes thereof toward said baffle structure and having U-shaped intermediate portions extending away from said bank into the interdeck space and along portions of said baffle structure for supporting 30 the latter.

3. In a boiler having a pair of vertically spaced banks of inclined generating tubes, downcomer and riser headers for said banks, and a baffle structure extending through said upper bank, across 35 the space between said banks and along part of the upper row of tubes in the lower bank to separate the first gas pass from the second; a row of generating tubes having end portions connected to the lower ends of the headers of said upper 40 bank and having intermediate portions thereof bent away from said bank in substantially U-shape and extending along parts of said baffle structure for supporting the latter.

4. In a boiler having a pair of vertically spaced 45 banks of inclined generating tubes, downcomer and riser headers for said banks, and a baffle structure extending through said upper bank, across the space between said banks and along 50 part of the upper row of tubes in the lower bank to separate the first gas pass from the second; a row of tubes connected at opposite ends to the headers of one of said banks and each having an intermediate portion thereof deflected away from 55 said one bank and extending along a portion of said baffle structure for supporting the latter, the tubes of said baffle supporting row having two separate sections; and header means located adjacent said baffle for connecting said sections.

5. In a boiler having inclined generating tubes 60 arranged in a pair of banks spaced vertically and providing an interdeck space; downcomer and riser headers for said banks, and a baffle structure for separating the first gas pass from the second comprising a part extending vertically between 65 the tubes of the upper bank and across the interdeck space and another part inclined along the upper row of tubes of the lower bank; a row of generating tubes having their end portions connected to the headers of said upper bank and extending parallel to the tubes of the latter with intermediate portions thereof deflected away from 70 said upper bank into the interdeck space and extending along the vertical and inclined parts of said baffle structure for supporting the latter. 75

6. In a boiler having inclined generating tubes arranged in a pair of banks spaced vertically and providing an interdeck space; downcomer and riser headers for said banks, and a baffle structure for separating the first gas pass from the second comprising a part extending vertically between the tubes of the upper bank and across the interdeck space and another part inclined along the upper row of tubes of the lower bank; a row of generating tubes having end portions connected to the lower parts of the headers for said upper bank and having intermediate portions thereof spaced from the tubes of said upper bank and extending adjacent the lower bank along the inclined portion of said baffle for supporting the latter.

7. In a boiler having inclined generating tubes arranged in a pair of banks spaced vertically and providing an interdeck space; downcomer and riser headers for said banks, and a baffle structure for separating the first gas pass from the second comprising a part extending vertically between the tubes of the upper bank and across the interdeck space and another part inclined along the upper row of tubes of the lower bank; a row of generating tubes having their end portions connected to the headers of said upper bank and extending parallel to the tubes thereof toward said baffle and having intermediate portions deflected away from said upper bank and extending along opposite sides of one part of said baffle structure for supporting the latter.

8. In a boiler having inclined generating tubes arranged in a pair of banks spaced vertically and providing an interdeck space, downcomer and riser headers for said banks, and a baffle structure for separating the first gas pass from the second comprising a part extending vertically between the tubes of the upper bank and across the interdeck space and another part inclined along the upper row of tubes of the lower bank; a row of generating tubes having their end portions connected to the headers of said upper bank and extending parallel to the tubes thereof toward said baffle and having intermediate portions deflected away from said upper bank and extending along opposite sides of the vertical portion of said baffle for supporting the latter.

9. In a boiler having inclined generating tubes arranged in a pair of banks spaced vertically and providing an interdeck space, downcomer and riser headers for said banks; a row of generating

tubes having end portions connected to the lower parts of the headers for said upper bank and having intermediate portions thereof spaced from the tubes of said upper bank and extending along and adjacent portions of the tubes of the upper row of tubes of said lower bank; and a baffle structure including an inclined portion disposed above and extending along the uppermost row of tubes of the lower bank and extending partially above and partially below the said intermediate portions of said generating tubes to be supported thereby.

10. In a boiler having inclined generating tubes arranged in a pair of banks spaced vertically and providing an interdeck space, downcomer and riser headers for said banks, and a baffle structure for separating the first gas pass from the second comprising a part extending vertically between the tubes of the upper bank and across the interdeck space and another part inclined along the upper row of tubes of the lower bank; and a row of generating tubes connected at their ends to the headers for said upper bank and extending therefrom parallel to and closely adjacent the tubes of said bank for the greater portion of the length of said tubes, said row of tubes having intermediate portions extending across the interdeck space along opposite sides of the vertical part of said baffle structure for supporting the latter.

11. In a boiler having inclined generating tubes arranged in a pair of banks spaced vertically and providing an interdeck space, downcomer and riser headers for said banks, and a baffle structure for separating the first gas pass from the second comprising a part extending vertically between the tubes of the upper bank and across the interdeck space and another part inclined along the upper row of tubes of the lower bank; a row of generating tubes having their end portions connected to the headers of said upper bank and extending parallel to the tubes thereof toward said baffle and having intermediate portions deflected away from said upper bank and extending along opposite sides of the vertical portion of said baffle for supporting the latter, the tubes of said baffle supporting row having two separate sections; and header means located between the vertical and inclined parts of said baffle for connecting said tube sections.

WILBUR H. ARMACOST.
